UNITED STATES PATENT OFFICE.

JOSEPH McLEAN, OF ROCKVILLE, CONNECTICUT.

POCKET-RULE.

SPECIFICATION forming part of Letters Patent No. 378,894, dated March 6, 1888.

Application filed March 16, 1887. Serial No. 231,092. (No model.)

To all whom it may concern:

Be it known that I, JOSEPH McLEAN, a subject of the Queen of Great Britain, and a resident of Rockville, in the county of Tolland 5 and State of Connecticut, have invented certain new and useful Improvements in Pocket-Rules, of which the following is a full, clear, and exact description, whereby any one skilled in the art can make and use the same.

10 The object of my improvement is to provide a pocket-rule with a bevel or angle measuring device that shall be simple and compact; and to this end my improvement consists in a rule having a joint with a tongue on one part roughened on the edge or provided 15 with indentations or teeth, and the other part of the joint bearing a tilting locking device and having the outer surface of one of the cheek-pieces graduated; and it further consists in details of the several parts and their 20 combination, as more particularly hereinafter described, and pointed out in the claim.

Referring to the drawings, Figure 1 is a plan view of a part of a rule, showing the joint that 25 embodies my improvement, with parts broken away to show construction. Fig. 2 is a plan view of a part of a rule, showing the sections closed, with the joint that embodies the improvement broken away to show construction. 30 Fig. 3 is an end view of the rule with the joint closed.

In the accompanying drawings, the letter *a* denotes a carpenter's rule that may be of any material and construction; *b*, the joint that 35 unites the several parts of the rule edgewise, or in the direction of their width, as commonly made. This joint is composed of one part having a tongue, *b'*, that is fastened to one section of the rule by straps and rivets, 40 and of the joint part *c*, having a slot to receive the tenon between the cheek-pieces *c'*. This joint part is preferably formed of sheet metal folded to shape to fit upon the end of a section of the rule and extending along it a sufficient distance to afford a hold for the rivets by means of which the part is attached to the rule-section. The two parts of the joint 45 are united by means of a pin or pivot, *d*, so that when the sections are closed together

edgewise the line of division between the rules 50 passes through the center of the pivot, while the shoulders *a'* are in line with each other and on a line passing through the center of the joint and at about right angles to the line of division of the rule-sections. 55

The projecting semicircular part *e* of the joint is graduated—that is, divided into degrees or parts of degrees—so that when the rule is open the angular divergence of the sections of the rule that are united by this joint 60 may be measured by noting the position of the shoulder *a'* on the graduated arc marked on the projecting part *e* of the rule-joint.

In order to hold the rule-sections in a certain position after having measured the angle, 65 a catch or stop is used. This consists of a tilting block, *f*, hung within the fold of the joint-section *c*, near one edge, and with a hooked part, *f'*, that is adapted to engage with the roughened or indented periphery of the 70 tenon *b*.

The catch is moved into and out of engagement with the tenon by means of a sliding bolt, *g*, that is operated by means of the stud *g'*, that projects beyond the edge of the rule. 75 The lower surface of this bolt is beveled and slides upon the beveled back of the tilting catch. By means of this bolt the sections of the rule may be set at ninety degrees with each other, locked there, and the device used 80 as a square, or the section may be set at any desired degree and locked in that position, or the arc may be used for measuring bevels or slopes, as desired.

I claim as my invention— 85

In combination with the hinged sections of a rule, the joint *b*, composed of the tongue *b'*, with a roughened edge, the pivot *d*, and the socket *c*, the tilting block *f*, hinged within the fold of the joint-section and having the hooked 90 end *f'*, and the sliding bolt *g* with rounded face fitting the recessed back of the tilting block and having the projecting stud *g'*, all substantially as described.

JOSEPH McLEAN.
